UNITED STATES PATENT OFFICE

151,427

DESIGN FOR A HAIR COMB

Allan Bresn, Chicago, Ill.

Application March 26, 1947, Serial No. 137,917

Term of patent 14 years

(Cl. D86—8)

To all whom it may concern:

Be it known that I, Allan Bresn, a citizen of the United States, residing in Chicago, in the county of Cook and State of Illinois, have invented a new, original, and ornamental Design for a Hair Comb, of which the following is a specification, reference being had to the accompanying drawing, forming part thereof.

Fig. 1 is a side view of a comb, showing my new design;

Fig. 2 is a top view thereof.

I claim:

The ornamental design for a hair comb, as shown.

ALLAN BRESN.
